UNITED STATES PATENT OFFICE.

ROBERT J. COPELAND, OF TORONTO, ONTARIO, CANADA.

HINGE FOR LOOSE-LEAF-BOOK COVERS.

Application filed October 23, 1922. Serial No. 596,379.

The principal objects of the invention are to provide a simple, strong and durable form of hinge connection for loose leaf binders which will present a good appearance and 5 will enable manufacture at low cost.

The principal feature of the invention consists in providing a pivotal strap hinge connection between the back and cover, the looped strap members secured to one member 10 being loosely inserted through slots in a projecting tongue on the other member.

In the drawings Figure 1 is a sectional perspective view of a cover and back constructed in accordance with this invention.

15 Figure 1^a is an enlarged cross sectional view through the binder back shown in Figure 1.

Figure 2 is an enlarged perspective detail of a slightly modified form of the invention.

20 Figure 3 shows a perspective sectional detail of a further modification of the back structure.

Figure 4 is a sectional perspective detail of a still further modification.

25 In the construction of certain types of loose leaf binders, the "Back" 1 which supports the binder posts or contains the binder lock is usually made of pressed sheet metal in substantially rectangular form having the back and front edges rounded and it has been the custom to cover these with a suitable strong flexible fabric, the longitudinal edges of which are bound in the "cover" structure 2 and the fabric extending between the 30 "back" and "cover" forming the "hinge".

35 The present invention proposes the use of narrow strips of metal 3, to be doubled and secured by rivets or other suitable means, preferably to the cover, so that the looped portion 4 projects beyond the member to 40 which it is attached.

45 The other member is formed with a projecting tongue 5 in which are formed the slots 6. The straps 3 are inserted through these slots before being attached to the other member.

50 In the form of the invention illustrated in Figure 1 the sheet metal back 1 is formed up with the edge strip 7 projecting midway of the thickness of the back and the other edge is lapped around it, thus fastening the edges securely and providing a tongue of three thicknesses of metal. The slots 6 are punched through this projecting tongue and 55 the straps 3 are then inserted and the cover is secured thereto.

It may be found desirable to form the "backs" 1 in the usual manner and then place bands of sheet metal around them as illustrated in Figure 2, the bands having 60 their meeting edges formed similar to the tongue 5. Between these bands, the back may be covered with leather or fabric which will protect desks from being marked by the 65 metal.

When the full length strip is used as shown in Figure 1 the tongue 5 may be provided with notches 8 and bands of a suitable "cushion" material arranged to encircle the back, such bands being held in place by the notches. 70

The back may be formed in many different ways. The form illustrated in Figure 4 shows two strips of metal placed together with projecting strips 9 forming the hinge tongue. 75

In the form illustrated in Figure 3, the back is of the ordinary form and around this is placed a strip of fabric 10. The edges are lapped in a manner similar to the sheet metal, previously described and a strip of wire 11 80 is enclosed. Over the composite strip is inserted a U-shaped metal strip 12 which is pressed around the wire and clamps the fabric. The metal strip and the enclosed fabric is slotted the same as the other forms to receive the hinge straps 3.

85 From this description it will be readily understood that the invention may be applied in many different forms and if desired the hinge straps may form part of the "back" 90 structure and be connected to a slotted cover without departing from the spirit of the invention.

What I claim as my invention is:—

1. A hinge for loose leaf covers, comprising a binder back having a tongue formed of flat sheet strips extending longitudinally throughout the length thereof, said tongue having a plurality of spaced rectangular slots punched therethrough, and U-shaped 100 flat metal straps threaded through said slots and having their ends embracing the cover and rigidly secured thereto. 95

2. A hinge for loose leaf covers, comprising a binder back formed of a sheet of metal 105 bent longitudinally into a closed tubular form having the free edges overlapped and forming a longitudinal flattened tongue extending outwardly from one edge of the tube, longitudinally aligned slots cut in said 110 tongue leaving a continuous outer edge, and U-shaped flat metal straps inserted through

said slots and having their ends secured to the cover.

3. A hinge for loose leaf covers, comprising a binder back having edge flanges extending outwardly therefrom in overlapped relation, a longitudinally extending U-shaped metal strip inserted over said overlapped edge flanges and presenting a beaded outer longitudinal edge, longitudinally aligned

slots extending through said metal strip and 10 enclosed edge flanges leaving said outer beaded portion intact, and looped metal strips threaded through said slots and retained therein by said intact beaded portion and being secured rigidly to the cover at its free 15 ends.

ROBERT J. COPELAND.
